INTAGLIO PRINTING

Georges Kanitz, Saint-Cloud, France

Application October 23, 1939, Serial No. 300,862
In France October 26, 1938

6 Claims. (CL 101—232)

It is known to use in intaglio printing, machines for printing paper in the form of sheets. They are characterized by a system of nippers which serve to grip the sheets so as to keep them accurately in position. Between the diameter of the printing roll and of the presser roll, there exists a fixed ratio that only enables printing rolls of substantially identical diameters to be used.

It is also known to use in intaglio printing, machines that print on paper in reels; they offer the advantage of enabling printing rolls of widely different sizes to be used; on the other hand, they do not allow of printing on sheets of paper, and still less of passing the sheets through the machine several times, in order to effect printing in a plurality of colours.

The object of the present invention is to eliminate these drawbacks. The presser roll is covered with rubber, without any system of nippers. For gripping the sheet accurately, the present invention provides for the stoppage of the rotation of the printing roll before the presser roll is pressed against the surface of the printing roll, or more correctly against the sheet of paper which is engaged at that instant between the presser roll and the printing roll.

The rotation of the printing roll is obtained in any known manner. However, the driving force is not stopped when the roll stops, but continues to act on same uninterruptedly in the direction of the rotation, through a friction or other non-rigid transmission. The stoppage of the printing roll at a predetermined spot of its circumference is effected by the downward movement of the pressure system, before the presser roll comes into proximity with the printing roll.

The sheet to be printed is previously placed in the correct position on the margining table, so that its front edge is beyond the line of contact between the printing roll and the presser roll.

In order to prevent the sheet which thus passes over the inked printing roll from becoming dirty and from being moved out of position, the front edge of the margining table is movable. It can move up to the board in front of the presser roll that carries the projections, and thus form a continuous support for the sheet, enabling same to be correctly positioned. It will then be moved backwards to enable the presser to move downwards on to the printing roll. The presser, having moved down on to said printing roll which is stationary, therefore clamps the sheet to be printed, in a definite position. Owing to the elimination of the dynamic factors at the instant

when the sheet to be printed is gripped, the accuracy of this operation is greatly facilitated.

The presser roll then bears on the paper and this rotation feeds the sheet at the same time as it is printed.

The stoppage of the printing is produced by the presser roll's moving away from the sheet and from the printing roll.

In order to release the printing roll and enable it to rotate, the stopping device is withdrawn when the pressure reaches a predetermined value.

An embodiment of the machine according to the invention will now be described with reference to the accompanying drawings in which:

Fig. 1 shows a general view of the machine;

Fig. 2, a view on a larger scale of the margining device of the machine;

Fig. 3, a section along III—III of Fig. 1;

Fig. 4, a side elevation of Fig. 3.

The printing roll 1 is mounted with its shaft 2 on the rollers 3 which form bearings. The lifting apparatus 14—15—16—17—18, formed by a rack, pinions, a worm, a worm wheel and an actuating crank, is used to raise the rolls of different diameters to the operating height determined by the position of the margining table 4. The whole arrangement is mounted on the carriages 43 and 44 which move along the machine on the base 45 to enable rolls of different lengths to be printed on the same machine. The movement of said carriages is obtained by means of the crank 46 and the screw 47 which is provided with a left hand and a right hand thread so that the bearings of rollers 3 remain symmetrical with respect to the plane of symmetry of the machine.

The presser bearings 19 slide in the guideways 20 of the frame 21 (in order to simplify the drawing, only one side of the machine has been shown). The bearing 19 carries the rubber covered presser roll 7 and the rigid counter-presser roll 8; its upward and downward motion is imparted by a known mechanical or hydraulic means, the travel being limited for example by electric contacts. In Fig. 1, the mechanism of the upward and downward motion has been shown by square-threaded worms 24 and worm wheels 24^I, 24^{II}.

The rotary movement of the printing roll is imparted by the motor 41 which drives the loose pulley 29 by means of a belt, and the sleeve 28 and the roll 1 by means of the friction band 30 (Figs. 3 and 4). The device for stopping the rotation of the printing roll 1 is formed on the one hand by the pin 9 which is arranged in housings 42 on the bearing 19 and is held by the connect-

ing rods 10, 11, and on the other hand by the sleeve 27 (fixed on the shaft 2 of the roll 1) provided with a notch 26.

When the system 7, 8, 19 is remote from the roll 1, the latter rotates freely (see Fig. 2). As the downward movement of the pressure system is produced through the motor 39, the pin 9 encounters, as it moves downwards towards the roll, the notch 26 of the sleeve 27 and stops the roll 1 in a predetermined position.

In order to decrease the impact between the parts 9 and 27, a mechanical, electrical or hydraulic braking system, not shown in the drawing, is provided which acts on the rotating mass of the roll 1 during the period prior to the contact between said parts.

The actuating motor 41 does not stop acting through the system 28, 29, 30 on the roll 1 in the direction of the rotation, even during the stoppage caused by the pin 9, in order to prevent any reverse motion of the roll. The actuating device 41 may be adapted solely to rotate the roll 1 when the pressure of the roll 7 is not being exerted, that is to say when running light. It may be assisted, at the instant when the sheet to be printed passes and when the presser roll 7 bears against the printing roll 1, by the actuating device 40 which is more powerful. The latter acts through the pulley 43 on the counter-presser 8 which transmits the force to the presser 7 and thence to the roll 1 by friction.

The pressure system is moved away from the roll 1 by means of the motor 39 by reversing its direction of rotation for the downward movement.

The feed table 4 is provided with a movable table portion 5 which, being actuated by the crank 6 and driven by the racks and pinions 34 and 32, can move towards the presser and even beyond its line of contact with the printing roll. It can be moved backwards to leave room for the presser 7. On the same driving shaft 35 are mounted sheet-flatteners 33 for holding the margined sheet when the table moves backwards. It is of course understood that the sheet-flatteners may be mounted on another shaft and be actuated independently before the movement of the table portion 5. In front of the roll 1, on the opposite side to the feed table is located the stripper 135, and the front gauge 36, against which the sheet 37 abuts to ensure its accurate positioning for printing (see Fig. 2).

A scraping device 31, such as is known in intaglio printing machines, is arranged below the feed table.

The machine operates as follows:

The roll 1 is set in motion by means of the system 28-29-30 (friction drive). The roll turns in the ink contained in an ink receptacle 38 and the scraper 31 wipes the excess of ink from its surface. The pressure system comprising the presser bearing 19, the presser roll 7, the counter-presser 8, and also the pin system 9-10-11-12-13, is moved away from the roll 1, which continues to rotate without stopping (Fig. 2). A sheet is placed on the feed table 4, the table portion 5 is moved forwards by means of the crank 6 up to the board 135 (see Fig. 2) and the sheet 37 is allowed to slide up to the projection 36. It is of course understood that on this machine there also exists a so-called "side" gauge which limits the position of the sheet in the longitudinal direction. When the sheet has been margined, the table portion

5 is moved backwards by rotating the crank 6 in the direction of the arrow, which has the effect of lowering the sheet flatteners 33 on the table so that they keep the sheet in its correct position.

The pressure system is then lowered towards the roll 1. Before the presser 7 comes into contact with the roll 1, the pin 9 enters the notch 26 of the sleeve 27 and stops the roll 1 rotating (Fig. 2). As the downward movement of the pressure system continues, the presser 7 comes into contact with the sheet 37 and presses it in its correct position against the roll 1. If the downward movement of the pressure system 15 is further continued, the presser 7 being held stationary on the surface of the roll 1, the screw 24 will compress the spring 25 and the movement of the rack 13 will actuate the pinion 12 and the lever 11 in the direction of the arrow (see Fig. 1) and, by means of the connecting rod 10, will withdraw the pin 9 from the notch 26. The roll 1 being thus released will start rotating again through its friction drive 41-28-29-30, carrying with it the sheet 20 37. The drive 41 may be helped or replaced by the drive 40 which will only start rotating when the spring 25, by means of the connecting rod 10 and the lever 11 has moved the pin 9 out of the notch 26, which can be effected by means 25 of an electric contact not shown.

The sheet 37 is grasped by its front edge at 30. Said sheet issues printed from the machine at the speed of rotation of the roll 1.

Before the sheet 37 has completely passed 35 under the presser 7 the motor 39 moves the latter away from the surface of the roll 1.

When the printing of the sheet is completed, only the roll 1 continues to rotate, up to the instant when a second sheet has been margined 40 and the operation begins again.

For printing a second colour on the same sheet, the second roll is placed on the machine by fixing the driving sleeve 28-29-30 and the sleeve 27 on the shaft 2 of the roll 1. The sleeve 27 is moved in the circumferential direction until the notch 26 comes approximately opposite the same spot of the engraving as on the first roll. The accurate registering can be obtained by means of gauges 36 which are adapted to undergo very considerable movements, such movements being in no way hindered by the nipper system, as is the case in the other machines for printing sheets. All the other operations remain invariable.

5. While I have illustrated and described the preferred form of construction for carrying my invention into effect, this is capable of variation and modification, without departing from the spirit of the invention. I therefore do not 60 wish to be limited to the precise details of construction set forth, but desire to avail myself of such variations and modifications as come within the scope of the appended claims.

What I claim is:

1. In an intaglio printing machine the combination comprising a printing roller, means for raising and lowering said printing roller, a presser roller adapted to cooperate with said printing roller, a counter-presser roller cooperating with said presser roller, means for moving said presser roller towards and away from said printing roller, means for rotating said printing roller and locking means for stopping said printing roller in a predetermined position before the printing operation.

2. In an intaglio printing machine the combination comprising a printing roller, means for raising and lowering said printing roller, a presser roller adapted to cooperate with said printing roller, a counter-presser roller cooperating with said presser roller, means for moving said presser roller towards and away from said printing roller, means for rotating said printing roller and means for locking said printing roller in predetermined position before said presser roller upon its movement towards said printing roller presses the sheet to be printed against said printing roller.

3. In an intaglio printing machine the combination comprising a printing roller, means for raising and lowering said printing roller, a presser roller adapted to cooperate with said printing roller, a counter-presser roller cooperating with said presser roller, means for moving said presser roller towards and away from said printing roller, means for rotating said printing roller, means for locking said printing roller in predetermined position before said presser roller upon its movement towards said printing roller presses the sheet to be printed against said printing roller and automatic means for restarting the rotation of said printing roller after complete contact has taken place between said presser roller and said printing roller.

4. In an intaglio printing machine the combination comprising a printing roller, means for raising and lowering said printing roller, a presser roller adapted to cooperate with said printing roller, a counter-presser roller cooperating with

said presser roller, means for moving said presser roller towards and away from said printing roller, means for rotating said printing roller and locking means for said printing roller controlled by the relative positions between said presser roller and said printing roller.

5. In an intaglio printing machine the combination comprising a printing roller, means for raising and lowering said printing roller, a presser roller adapted to cooperate with said printing roller, a counter-presser roller cooperating with said presser roller, means for moving said presser roller towards and away from said printing roller, means for rotating said printing roller, locking means for said printing roller controlled by the relative positions between said presser roller and said printing roller and driving means for said counter-presser roller designed to cooperate with said printing roller driving means.

6. In an intaglio printing machine the combination comprising a printing roller, means for raising and lowering said printing roller, a presser roller adapted to cooperate with said printing roller, a counter-presser roller cooperating with said presser roller, means for moving said presser roller towards and away from said printing roller, means for rotating said printing roller and locking means for stopping said printing roller in a predetermined position before the printing operation, said means for rotating said printing roller comprising a slip drive which operates during the locking of said printing roller.

GEORGES KANITZ.
